UNITED STATES PATENT OFFICE.

PERLEY R. GLASS, OF QUINCY, MASSACHUSETTS, ASSIGNOR, BY MESNE ASSIGNMENTS, TO
THOMAS G. PLANT, OF BOSTON, MASSACHUSETTS.

TACK OR NAIL DRIVING DEVICE.

No. 888,485.

Specification of Letters Patent. Patented May 26, 1908.

Application filed December 9, 1905. Serial No. 291,065.

To all whom it may concern:

Be it known that I, PERLEY R. GLASS, a citizen of the United States, residing at Quincy, in the county of Norfolk and State 5 of Massachusetts, have invented an Improvement in Tack or Nail Driving Devices, of which the following description, in connection with the accompanying drawings, is a specification, like letters on the drawings 10 representing like parts.

My invention relates to implements for driving tacks or nails and consists more particularly in improvements which simplify the construction and operation and increase 15 the efficiency thereof.

Although it may have other and more extensive application, in its illustrated embodiment my invention is shown as applied to a hand tacking device of the type where 20 the tacks are fed from an inclined channeled nail holder or magazine into a driver head and beneath a reciprocatory plunger, the driver head being provided with devices constructed successively to separate the 25 tacks from the line of tacks held in the magazine and to bring and hold the separated tacks in position to be driven by the forward movement of the plunger.

One object of my invention is to simplify 30 the separator mechanism, render it readily accessible and open for inspection, and less susceptible to impairment.

These and other objects of my invention will be best understood by reference to the 35 following description when taken in connection with the accompanying drawings showing for illustrative purposes one selected embodiment thereof, while its scope will be more particularly pointed out in the appended claims.

In the drawings.—Figure 1 is a side elevation, in partial section, showing a hand tacking device embodying one form of my invention; Fig. 2 is a section taken on the line 40 2—2 in Fig. 1; Fig. 3 is a section on an enlarged scale, partially broken away and taken through the driver and lengthwise the track channel or race-way; Fig. 4 is a section in plan taken on the line 4—4 in Fig. 3; Fig. 5 is a section similar to Fig. 3, taken 45 however in a transverse plane passing through the plunger rod and the barrel of the sliding separator and showing the latter in its normal position; Fig. 6 is a similar 50 view showing the plunger rod depressed and

the separator in its out position; Fig. 7 is a perspective view of the separating block; Fig. 8 is a section in plan taken where indicated by the line a—a in Fig. 7; Fig. 9 is a perspective view of the head block; Fig. 10 is a perspective in section taken on a line 55 slightly above the line 4—4 in Fig. 3 and showing the separator block in its normal or "in" position, and Fig. 11 is a similar perspective showing the out position thereof. 60

Referring to the illustrative embodiment of my invention shown in the drawings, and more particularly to Figs. 1 and 3, there is provided a tack or nail driving head a, having formed thereon a handle portion comprising 65 an upright hollow sleeve a' in which is slidably mounted the hollow plunger a². The latter is provided at its lower end with the closed solid head a³ in which is pinned or otherwise fixedly secured the driver-rod b, and the shorter plunger-rod c, the latter lying 70 parallel with and adapted to move coincidentally with the driver. The hollow plunger is normally held elevated or retracted through the medium of the inclosed interior spiral 75 spring a⁴, which being initially compressed bears at its lower end upon the round stationary stud a⁵ and at its upper end against the threaded plug a⁶ adjustably screwed into the open outer end of the plunger. The stud a⁵, 80 as shown in Fig. 2, passes transversely through the hollow sleeve, having threaded engagement with the walls thereof, and also through longitudinal slots a⁷ oppositely formed in the sides of the hollow plunger 85 acting to guide and prevent the latter from turning. The plunger therefore if forced 90 down by the blow of a hammer delivered upon its enlarged projecting head end will be quickly restored to its normal retracted position by the action of the spring a⁴, the stud a⁵, by abutting against the plunger head a³, acting as a limiting stop to outward or backward 95 plunger movement. The stud a⁵ being held in position by threaded engagement with the 100 walls of the sleeve only is free to be withdrawn at any desired time.

Near its base the head a is fashioned or recessed at one side to receive the head block d (separately shown in Fig. 9), the latter being 105 screwed, or otherwise suitably fastened in fixed position to and within the head. The said block has a vertical driving passage d' maintained in fixed alinement with the driver b, and in alinement also with a continua- 110

tion of the driving passage formed in the depending cone-shaped foot e threaded into the bottom of the head. The driving passage is of sufficient size to accommodate the tacks or 5 nails intended to be driven, and suitable means are provided for admitting the tacks laterally thereto beneath the plunger and for there holding the admitted tack to be driven on descent of the driver. For this purpose 10 there is provided the inclined tack holder or magazine f comprising an elongated casing having a rectangular slot or channel f' of sufficient width to receive the bodies of the tacks, while the heads thereof rest upon the 15 upper face or edges of the casing and are covered by the inclined protecting plate f^2 . The casing f is fixedly bolted, or otherwise secured, to the side of the lateral arm a^8 , the latter inclined upwardly and outwardly from 20 the driver-head, and there is thus formed an inclined channel or way down which the tacks tend to gravitate in a single column toward the driving head.

The upper and opposite end of the casing 25 is provided with suitable means, such for example as the spring clasps f^3, f^4 shown, which permit the same to be secured or otherwise placed when the instrument is at rest in operative relation to suitable replenishing apparatus for maintaining the channel or way of the magazine filled with a supply of tacks. The construction of this replenishing and loading apparatus being immaterial so far as the tack driving and separating mechanism is 35 concerned, further reference thereto is unnecessary. It is also to be understood that while the magazine f is of convenient and suitable form, any storage receptacle or tack feeding devices which will coöperate in the 40 proper way with the separating and driving means may be used in connection therewith.

The lower end or nose of the magazine frame f when it abuts against the head block d is cut away to receive a projecting part d^3 45 (Fig. 9) of the block, the latter having formed therein an aperture consisting of a T-slot d^2 , which is held in alinement with the channel slot of the magazine to permit passage of the tacks therefrom to the driving passage.

For separating the foremost tack from the line of tacks fed through the magazine to the driving head and for moving the separated tack through the T-slot and into the driving passage d' beneath the plunger, there is provided a tack-separating device herein consisting of the reciprocatory hook or jaw g' carried upon the sliding separating block g , the latter mounted in the head block for reciprocating movement toward and from the 50 driving mechanism. To give a firm unyielding sliding bearing, the separator block is provided with the rearwardly extending barrel g^2 which has a sliding fit in a transverse tubular box formed (Fig. 5) partly in the head block d and partly in the driving head a ,

and with the separator block is adapted to move from the position shown in Figs. 5 and 10 to that shown in Figs. 6 and 11.

The separator block is yieldably held to its normal or "in" position by a spring-pressed plunger h (Fig. 5) the nose of which engages a depression g^3 (Fig. 11) in the outer face of the block. The plunger slides in a barrel h^2 carried by the swinging arm h^2 , the latter swiveled to the driving head upon the stud h^3 . While the plunger is normally spring-pressed by the spiral spring h^4 within the barrel to maintain the separator block in its "in" position, it may be forced back into the barrel by pressure upon the block, or may be withdrawn to release the block by retraction of the thumb nut h^5 secured to the projecting stem of the plunger at its outer and opposite end. When thus retracted the plunger may be swung aside with and upon the arm h^2 and free access had to the driver-head for the removal of the separator block, or for other purposes.

When the block is in its "in" position, the outer edge of the separator jaw lies across the tack channel or slot f' (see Figs 3 and 10) and by closing the latter prevents the admission of tacks from the magazine to the T-slot and driving passage. For the feeding of successive tacks to a position beneath the plunger, the separator block is intermittently moved to withdraw the separator jaw from the mouth of the tack channel, and for this purpose the separator barrel g^2 is provided (Figs. 5 and 7) with a vertical slot g^4 having an inclined or beveled wall g^5 sloping upward and outward, the upper edge of which, on the "in" position of the separator block (Fig. 5) lies within the path of the beveled lower edge c' of the plunger rod. As the latter descends, it passes through the opening c^2 provided for that purpose in the driving head and the head block and enters the slot g^4 , where, by the pressure of the beveled edge c' of the plunger rod upon the beveled wall g^5 of the slot, it thrusts aside the separator block against the pressure of the spring h^4 into the out position shown in Fig. 6. The separator jaw thus thrown laterally by the descent of the plunger rod assumes the position best indicated in Fig. 11, opening the tack channel to permit entrance of nails to the T-slot d^2 in the driving block.

With the descent of the plunger rod c , however, the driver also descends and in advance thereof, so that when the mouth of the channel slot is opened by the withdrawal of the separator jaw, the foremost tack passes into the T-slot but against the side of the driver then occupying the driving passage, where the foremost tack, as well as the entire line or column is held against further movement, as best indicated in Fig. 11. On the retraction or rise of the plunger, the plunger rod is raised and withdrawn from engagement

with the slot of the separator block and the spring h^4 acts to return the block to its normal position. The separator jaw is so shaped and located, however, that when advanced 5 inwardly the point thereof will enter between the foremost tack, now within the T-slot of the driver block, and the next one of the line whereby the foremost tack will be separated from the remaining ones in the magazine. 10 The form of the curved inner face or edge of the jaw g' is such that during inward movement thereof after its point has separated or seized a tack in the manner described the latter will be carried or pressed inwardly by 15 the action of the curved face of the hook towards and within the driver passage as soon as the driver retracts sufficiently to open or expose the same. When the tack is expelled from the slot into the driver passage the separator block with its separating jaw is permitted 20 to complete its inward or closing movement. The tack thus delivered and admitted to the driver passage falls from its position of entrance into the position shown in 25 Fig. 3, where it rests (Figs. 3 and 4) upon the nose of a yieldable retaining pin i , which projects laterally slightly into the driver passage. The driving head is bored laterally to receive 30 a spring i' , which is retained by the threaded plug, but which bears against an enlarged head of the pin i , thereby normally pressing the same into its position of entrance within the driver passage, but permitting the same to yield to release the tack when the same is 35 struck by the driver on descent of the latter.

The complete operation of the described device will now be clear. When the implement is suitably supplied with tacks and in operation, a tack previously separated and 40 forced into the driving passage by the jaw g , is there retained by the yielding retaining pin i , below the jaw, however, and in position for driving beneath and within the path of the driver. The outer curved edge of the separator 45 jaw is in position across the tack slot of the holder, thereby closing the same and holding the tack or line of tacks therein. When the driver is depressed to drive the tack, its lower end striking the tack-head, will thrust aside 50 the yielding pin i and release the tack, which passes down the driving passage before the driver and into the work, against which the bottom of the foot e is held. The release and 55 descent of the tack is quickly followed by the descent and entrance of the plunger rod into the vertical slot g^4 of the separator block, imparting an endwise movement to the latter. The resultant withdrawal of the separator jaw from the foremost of the line of tacks 60 permits the advance of the latter against the depressed driver, further movement of the said tacks being prevented until the lower extremity of the subsequently ascending driver has passed a height sufficient to clear 65 the head of the foremost tack. Before this

occurs, however, the plunger rod c has released the separator block and the point of the separator jaw passes between the first and the next adjacent tacks. The inner edge of the jaw engages and presses against the shank or body of the foremost tack and the outer edge thereof against that of the next adjacent tack. The jaw, being then permitted to complete its inward movement, swings the foremost tack into the driving passage and the body of the next tack is swung somewhat backward, as shown in Fig. 3. The tack thus fed to the driving passage descends until caught upon the retaining pin, where it is held in readiness for the next stroke 80 of the driver.

From Figs. 4, 7, 8 and 9 it will be seen that the lower portion of the driving passage where it intersects the head block d , is formed in part by the walls of the separator block 85 and that the latter, where so formed, symmetrically completes the cylindrical passage without contraction thereof and offering no resistance or obstacle to the downward passage of the tack. Each tack on admission to the driving passage is restrained from passing to the bottom thereof and out of its mouth, if the latter be uncovered, by the sliding pin i alone. This construction is to be preferred 90 to that where the separator is so formed as to contract more or less the driving passage and thus provide a rest for the tack on its admission thereto, the separator yielding and moving outwardly to withdraw the contracted portion or rest from beneath the tack 95 head and release the latter on impact of the driver thereagainst. In the construction here disclosed the separator block has the simple function of separating and feeding the 100 tacks and is required to undergo no initial movement to release the tack already in the passage, but only a feeding and separating movement under the sole control of the plunger-rod c . This simplifies both the 105 movement and the construction of the separator mechanism and better assures its positive and accurate movement for the separation and feeding of the tacks.

The accuracy of operation and simplicity of construction, and particularly the integrity of adjustment, of the working parts are 110 greatly enhanced by the use of the solid and substantial sliding separator, the latter having ample bearing surface for maintaining correct alinement, as distinguished from a swinging or hinged separator, the use of which in practice must be accompanied by relatively diminished bearing surface and a more uncertain alinement and delicate construction.

The use of the sliding separator, moreover, 115 is particularly advantageous in connection with the swinging or removable retaining arm, for, on withdrawal of the arm to release the separator block, the latter may be 120

125

130

entirely removed from the head-block, giving access to, and free inspection of, the tack passages therein.

Claim.

- 5 1. A hand-tacker provided with a driving passage and a tack-passage leading thereto, a longitudinally sliding, separating device for separating and feeding the tacks into the driving passage, the walls of the separating device forming a continuous part of the driving passage, said passage being of uniform area contiguous said separating device, a reciprocating driver and means to engage and move said separating device.
- 10 2. A hand-tacker having a reciprocating driver and longitudinally-slidable tack-separating device constructed to aid in the formation of a continuous driver passage, provided with a bearing member extending into the body of the implement, and a plunger-rod for engaging the separating device to move the same and means independent of the plunger rod for returning the sliding tack separating device to initial position.
- 15 3. A hand-tacker having a reciprocatory separating-device, an arm, and a spring-pressed member upon said arm, for holding said separating device in position said arm being mounted to swing out of the path of movement of the separating device.
- 20 4. A hand-tacker having a reciprocatory separating-device, spring-pressed means for holding the same in position, and a movable support for said spring-pressed means where-

by the latter may be withdrawn from engagement with said separating device.

5. A hand-tacker having reciprocatory separating-means, a member yieldably holding said separating-means against movement in one direction, a swinging arm supporting said member, and means for manually withdrawing said holding means from said separating-means.

6. In a hand-tacker, the combination with separating-means, of a movable arm, a barrel carried by said arm, and a spring-pressed plunger movable in said barrel and adapted for engagement with said means, said plunger having a projecting stem for manual engagement.

7. A hand tacker comprising, in combination, a driving head *a*, a head-block *d*, and a sliding, separating block *g*, said head-block and sliding, separating block having walls forming complementary uncontracted portions of a driving passage, a driver *b*, and means acting positively to slide the separating block in one direction and a spring acting on the block for sliding it in the opposite direction.

In testimony whereof, I have signed my name to this specification, in the presence of two subscribing witnesses.

PERLEY R. GLASS.
